DARIUS T. WADHAMS, OF OSWEGO, NEW YORK, ASSIGNOR TO NIEL GRAY, JR., OF OSWEGO, NEW YORK.

FEEDING AND SPACING MECHANISM FOR CUTTING-MACHINES.

1,273,959.

Specification of Letters Patent. Patented July 30, 1918.

Application filed January 20, 1916. Serial No. 73,115.

To all whom it may concern:

Be it known that I, DARIUS T. WADHAMS, a citizen of the United States, residing at Oswego, in the county of Oswego and State 5 of New York, have invented new and useful Improvements in Feeding and Spacing Mechanism for Cutting-Machines, of which the following is a specification.

My present invention consists of a feeding 10 and spacing mechanism for cutting machines and has for its purpose to facilitate the cutting up of the stock into small pieces. To this end it comprises means associated with the usual back gage and operative to 15 advance the gage with successive, accurately measured feed movements so that the work is uniformly advanced to the cutting knife.

As is well understood, mechanism for the described purpose has a utility of great 20 value in the cutting up of large sheets upon which labels or other similar small matter is printed and is to be severed. It is of particular value in the commercial type of cutting machines employed in the cutting of 25 cloth samples as are largely distributed by cloth houses. In either instance the material to be cut up ordinarily comes in sheets of considerable length and width and is to be cut into small pieces of but a few inches in 30 dimension. This work therefore requires a progressive feeding forward, a few inches for each cut, of long length of material and this is very easily effected by the mechanism of my invention.

Particular features of my invention consist in an improved construction and arrangement of spacing mechanism adapted to operate in connection with means for manually advancing the gage in a manner to 35 permit of independently advancing the gage as desired; in providing for adjusting of the stops of the spacing device to fixed relations for measuring the advance of the gage for both lengths and widths and further of an 40 improved arrangement for conveniently disconnecting the spacing device to permit of manually moving the gage independently thereof and to permit of this being effected without requiring the manipulation of additional parts.

An improved embodiment of my invention is illustrated in the accompanying drawing wherein the reference characters of this description are applied to the corresponding parts in the several views. There-

in Figure 1 is a longitudinal sectional view showing my improved mechanism applied to a standard type of cutting machine; Fig. 2 is a partial plan view showing the spacing mechanism; Fig. 3 is a similar view showing the parts in released position; Fig. 4 is a detail sectional view showing the removable stop and Fig. 5 is a partial detail view of the clutch roller arrangement.

In the embodiment of my invention here 65 shown 1 indicates the standard of a cutting machine supporting the usual cutting table 2 upon which the stock to be cut is placed so as to be severed by the knife 3. This knife operates in a vertical plane during the 70 cutting stroke desirably so as to produce a shear stroke and, as in the usual way, may cut into the cutting stick 4 or, if desired, the stock to be cut may be placed upon one or more cutting boards positioned on the table 75 to slide thereon and the knife adjusted to cut into these boards. To the rear of the knife the usual back gage 5 is slidably mounted on the table and provided on its under surface with a guide-lug fitted to the 80 usual guide-slot in the rear of the table.

In the present instance, to the under surface of the gage there is attached a lug member provided with lugs 6-6 for attaching thereto the ends of an operating chain 7. 85 The chain 7 is carried by suitably journaled front and rear sprockets of which the front sprocket 8 is here shown journaled indirectly upon a bearing stud 10 secured to a bracket 11 attached to the under side of the 90 table at the front of the machine. The rear sprocket 12 is shown secured to a collar 13 and journaled on a rear bearing stud 14 at the extreme rear of the table.

The front sprocket 8 is here shown fixed 95 upon the hub or bearing collar 16 of a hand wheel 18 whereby upon rotation of the hand wheel member the back gage will be moved forward or back. This movement of the gage may be effected in both directions by 100 manual operation of the hand wheel 18 and in addition thereto means are provided for advancing the gage with measured feed movements as now to be described.

Desirably my improved spacing device is 105 arranged to operate through or upon the hand wheel member for advancing the gage. Accordingly it is here so shown and comprises an annular disk 20 fixed on the hub 16 and provided on its peripheral surface with 110

a hardened steel ring 21 which may be shrunk thereon. Suitably journaled with relation to this disk 20 is an operating or spacing lever 25, this lever being here shown 5 provided with a hub flange 26 journaled upon the bearing flange 16.

Interposed between the disk 20 and the spacing lever a suitable clutch is provided to couple said parts upon the movement of 10 the spacing lever in the direction for advancing the gage. For this purpose I have provided a hardened steel roller 30 arranged between the hardened ring 21 and a hardened steel plate set at an angle in the lever 25. A spring 32 is fitted to a socket in the spacing lever to act upon the roller to hold it in binding engagement between the ring and plate. Thus upon moving the spacing lever in one direction this clutch roller 30 20 will bind and couple the handle-member thereto to communicate the motion to the gage. Upon the reverse movement of the spacing lever the roller will ride freely in the larger end of the groove formed between the plate and the ring thereby permitting of return movement of the spacing lever independently of the connections.

Associated with the spacing lever I have arranged a stop ring 35 loosely mounted 30 upon the bearing hub 26 of the spacing lever. This stop ring is adapted to be clamped to the spacing lever 25 when it is desired to adjust the movement imparted thereby to the gage. For this purpose a 35 clamping clip 36 is carried on the lever and adapted to engage the stop ring and to rigidly clamp the ring to the lever upon the tightening of the pinch screw 37. Upon the top surface of this clamping ring I have 40 arranged a suitable stop 40 which as shown is desirably removably fitted to a pin 41. To coat therewith there are arranged stationary stop pins 43-44 here shown secured to the bracket 11. As best shown in Figs. 45 2 and 3, the pin 43 is arranged slightly farther away from the center of the hand wheel member than the stop pin 44. It is designed that the removable stop 40 shall coat with the pin 44 for determining the extent of 50 movement imparted to the gage by the spacing lever during one spacing operation; the extent of movement being limited by the engagement of the stop 40 with the pin 44.

The initial or return stop for the spacing 55 lever is provided by the engagement of a pin 45 on the spacing lever with the opposite side of the stop pin 44. This pin 45 is arranged on the opposite side of the clutch roller 30 from the spring 32 and is loosely 60 fitted to an aperture in the lever and is adapted to engage the stop pin 44 to limit the return stroke of the spacing lever and to determine its initial position. Upon so 65 engaging the pin 45 will be given a slight movement to release the clutch roller from

binding engagement between the ring 21 and plate 31.

A second or alternative movable stop 48 is here shown and is adapted to coöperate with the stop pin 43. This stop 48, as best 70 shown in Fig. 1 hooks over the stop ring 35 and is clamped thereto in any desired position by means of the screw 50 and tapered nut 51 threaded thereto so that upon turning the screw the tapered nut will cause 75 binding of the stop upon the ring. This stop, as shown, is provided with an engaging screw 53 threaded therein, the screw having a knurled thumb flange 54 and being provided with a knurled locking nut 55 80 to enable the operator to obtain a very fine adjustment of the stop with relation to the co-acting stationary stop pin.

To set the described spacing devices for any particular spacing, the spacing lever is 85 moved around to its extreme return position, until the pin 45 strikes the stop 44 and the clutch roller is released. This establishes the initial position. Upon loosening the clamping clip 36 the stop ring 35 is disengaged from the spacing lever and may be turned for adjusting the relation of the stop 40 thereon to its coacting stationary pin 44. This can be done by the operator holding this stop 40 in contact with its coacting pin 95 44 and moving the spacing lever 25 in the direction for advancing the gage. As soon as the pin 45 leaves the pin 44 the clutch roller will couple the spacing lever to the gage connections and thereafter upon further movement the gage will be advanced. By observing the extent of the movement then imparted to the gage, by the assistance of the usual indicator connected with the gage, the operator, when he has advanced 100 the back gage 5 the required distance may then lock the stop ring 35 to the spacing lever by tightening screw 37. The subsequent movement of the spacing lever will be confined between the stops thus relatively 105 positioned and upon operating the lever the gage will be advanced with successive feed movements of the length thus determined; the spacing lever being free from coupling engagement on the return stroke when the 110 clutch roller is released and when moved in the other or operating direction the clutch roller will bind and its motion will be transmitted to the gage through the chain connection.

A somewhat similar method is employed in setting the desired relationship of the movable stop 48 to the coacting pin 43 for governing the alternative feed movement to be given to the gage. In the latter instance 125 the stop instead of the ring is loosened and it is held against the coacting pin and tightened when the gage has been fed the distance desired. It will be understood that one adjustment is employed for widths and 130

the other for lengths. In the present instance the stop 48 is employed for the longer feed movements and becomes operative upon the removal of the first stop 40 which may 5 be simply lifted off its pin and thereafter the spacing lever will be limited in its movement only by the stop 48 for the longer feeds. The described arrangement of stops thus permits of rigidly setting the stops for 10 both widths and lengths and to employ either without changing the setting of the other, simply requiring the removal and replacing of the stop 40.

From the foregoing it will be seen that 15 when the spacing lever is shifted to one extreme position, *i. e.* with the pin 45 engaging the stop 44, that the operating connections to the gage will be released from the spacing device so that any desired adjustments of the gage may be made by rotating 20 the hand wheel 18. A further important feature is desirably associated with this arrangement consisting of means for normally retaining the parts in said released relation 25 but to permit of the use of the spacing mechanism without necessitating the removal or special manipulations of parts. I therefore provide a yielding holding pin 60 arranged in a suitable bearing in the spacing 30 lever and provided with a beveled inner end positioned to engage the stop pin 44 whenever the lever is pushed back to initial position; the pin then engaging behind said pin so as normally to retain it in this position. The holding pin 60 is spring pressed 35 by a spring 61 fitted within the socket 62 of the spacing lever and confined behind the head of the pin. The beveled end surfaces of the pin permit it to yield, against the influence of the spring, when the space lever 40 is operated whereby said space-lever is at all times operable. When a quantity of spacing is to be done it is desirable to render the holding pin 60 ineffective so I have provided the pin 60 with a cross-pin 64 normally positioned within a slot 65 and adapted 45 to rest against a shoulder 66 when the pin is withdrawn and given a partial turn, as shown in Fig. 3. In this position the holding pin 61 clears the stop-pin 44.

The spacing lever is arranged to be under the table as shown to be out of the way in its normal position when disengaged. Beneath the hand-wheel 18 is shown the usual 55 clamping lever 68 which serves to lock the wheel when moved in one position for rigidly locking the gage.

While I have shown and described a desirable embodiment of my invention it will 60 be understood that many modifications thereof may be made without departing from the scope of the invention. It is therefore intended that all matter contained herein shall be interpreted as illustrative and not 65 in a limiting sense.

Having described my invention I claim,

1. In a cutting machine, the combination with the frame and a table for the work thereon, of work advancing mechanism, an actuating member therefor, a spacing lever 70 suitably journaled, coupling means interposed between the spacing lever and the actuating member and adapted to couple said lever and member to move together in one direction and adapted to permit an independent return movement of the lever, stops suitably arranged to limit the movement of the spacing lever and said means being operative to release the spacing lever from coupling engagement when in initial 75 position.

2. In a cutting machine, the combination with the frame and a table for the work thereon, of work advancing mechanism, an actuating member therefor, a spacing lever 80 suitably journaled, a coupling roller interposed between the spacing lever and the actuating member and adapted to couple said lever and member to move together in one direction and adapted to permit an independent return movement of the lever, stops suitably arranged to limit the movement of the spacing lever and engaging means positioned to engage the roller so as to release the spacing lever from coupling 85 engagement when in its initial position.

3. In a cutting machine, the combination with the frame and a table for the work thereon, of work advancing mechanism, an actuating member therefor, a spacing lever 100 suitably journaled, a coupling means interposed between the spacing lever and the actuating member and adapted to couple said lever and member to move together in one direction and to permit an independent return movement of the lever, said coupling means being adapted to be released when the lever is in its initial position and means for retaining the lever in said initial position.

4. In a cutting machine, the combination with the frame and a table for the work thereon, of work advancing mechanism, a spacing lever suitably journaled, coupling means adapted to couple the lever and connections to move together in one direction and adapted to permit an independent return movement of the lever, stops suitably arranged to limit the movement of the spacing lever, and a yielding retaining means 115 normally to retain the lever in its initial release position substantially as described.

5. In a cutting machine, the combination with the frame and a table for the work thereon, of work advancing mechanism, a hand actuated member therefor, a spacing lever suitably journaled, a coupling means interposed between the spacing lever and the actuating member and adapted to couple said lever and member to move together in 120

110

115

120

125

130

one direction and to permit an independent return movement of the lever, means to engage and release the coupling member when the lever is in initial position, and a 5 yielding catch element arranged normally to retain said lever in initial position and adapted to be moved to an inoperative position when desired substantially as described.

10 6. In a cutting machine, the combination with the frame and a table for the work thereon, of work advancing mechanism, an actuating member therefor, a spacing lever suitably journaled, coupling roller interposed between the spacing lever and the actuating member and adapted to couple said lever and member to move together in one direction and to permit an independent return movement in the opposite direction, 15 stops suitably arranged to limit the movement of the spacing lever, said stops comprising fixed stops suitably supported and co-acting stops carried by the spacing-lever, one of said stops being removable, and 20 means operative automatically to release the clutch roller when in initial position substantially as described.

7. In a cutting machine, the combination with the frame and a table for the work 30 thereon, a back gage movably supported on the table, operating connections to said gage, an actuating member therefor, a spacing lever suitably journaled, coupling means interposed between the spacing lever and the 35 actuating member and adapted to couple said lever and member to move together in one direction and to permit an independent return movement of the lever, means to engage and release the coupling member when 40 the lever is in its initial position and a yieldable element carried by the lever and adapted to retain said lever in its initial position substantially as described.

8. In a cutting machine, the combination 45 with the frame and a table for the work thereon, a back gage movably supported on the table, front and rear bearing studs supported by the table, sprockets journaled on the bearing studs, an operating chain carried by the sprockets and connected to the gage, a hand wheel member journaled on the forward stud and connected to the forward sprocket, a spacing lever journaled on the hand wheel member, a stop ring arranged 50 concentric therewith and adjustable with relation to the spacing lever, means for securing the stop ring to the lever, a bearing disk on the hand wheel member, a coupling element interposed between the spacing lever 55 and the bearing disk and adapted to couple said lever and disk to move together in one direction and to permit independent return movement of the lever in the opposite direction, stops carried on the stop ring, fixed 60 stops arranged to coact therewith for de- 65

termining the extent of each feed movement and means operative to release the clutch element when the lever is in initial position, substantially as described.

9. In a cutting machine, the combination 70 with the frame and a table for the work thereon, of work advancing mechanism, a spacing lever suitably journaled, coupling means adapted to couple the lever and connections to move together in one direction 75 and adapted to permit of an independent return movement of the spacing lever, a stop supporting member connected to be movable with the lever and arranged to be adjustable with relation thereto, a fixed stop thereon 80 adapted to be adjusted with the support and a second stop thereon adapted to be adjustable with relation to the support and fixed stop means adapted to coact with the movable stops for determining the extent of 85 movement imparted to the connections substantially as described.

10. In a cutting machine, the combination with the frame and a table for the work thereon, of work advancing mechanism, a hand actuated member therefor, a spacing lever suitably journaled, a coupling means interposed between the spacing lever and the actuating member and adapted to couple 90 said lever and member to move together in one direction and to permit an independent return movement of the lever, a fixed stop arranged to determine the initial position of the lever and a yielding catch element arranged normally to retain said lever in initial position, said catch element comprising a plunger fitted to a socket in the lever arranged to engage the fixed stop and a spring acting thereon substantially as described.

11. In a cutting machine, the combination 105 with the frame and a table for the work thereon, of work advancing mechanism, a hand actuated member therefor, a spacing lever suitably journaled, a coupling means interposed between the spacing lever and the actuating member and adapted to couple 110 said lever and member to move together in one direction and to permit an independent return movement of the lever, a stop to determine the initial position of the lever, 115 means arranged to engage the stop and release the coupling member when the lever is in initial position, and a yielding catch element arranged normally to retain said lever in initial position and adapted to be moved 120 to an inoperative position when desired substantially as described.

12. In a cutting machine, the combination 125 with the frame and a table for the work thereon, of work advancing mechanism, a spacing lever suitably journaled, coupling means adapted to couple the lever and connections to move together in one direction and adapted to permit of an independent return movement of the spacing 130

lever, a stop supporting member connected to be movable with the lever and arranged to be adjustable with relation thereto, a stop detachably carried by the stop supporting member and adjustable therewith and a second stop thereon adapted to be adjustable with relation to the support and fixed stop

means adapted to coact with the movable stops for determining the extent of movement imparted to the connections substantially as described. 10

In testimony whereof I have signed my name to this specification.

DARIUS T. WADHAMS.
